HEAT EXCHANGER

William Sangster, Peterborough, Ontario, Canada, assignor to The De Laval Separator Company, New York, N. Y., a corporation of New Jersey

Application January 18, 1933, Serial No. 652,309

4 Claims. (Cl. 257—183)

This invention relates to a heat exchanger and has particular reference to a cooler or heater through which flow of a liquid is to take place through a series of tubes located adjacent each other and preferably parallel to each other.

The present invention has for its object the provision of a heat exchanger involving a plurality of headers and tubes extending between such headers. Heretofore such heat exchangers

10 generally consisted of headers in the form of castings provided with cored passages and openings into which tubes were fitted. This construction has disadvantages for several reasons among which may be mentioned the fact that considerable accuracy of tube length was required and the operations of securely fastening the tubes in the headers were carried out at relatively high temperatures and extended over long periods of time so that warping of the brass or copper tubing might result. Furthermore, the headers were quite heavy with the result that a heat exchanger having substantial heat exchange area had an inconvenient weight.

20 As contrasted with such arrangements the present invention has as its object the provision of a heat exchanger of such construction that it may be easily assembled out of standard parts, primarily consisting of tubing. As a result, it is quite cheap because of the use of tubing for the headers of light weight. Furthermore, assembly can be made at lower temperatures and in shorter times so that there is less tendency for warping of the tubes which are desirably thin 30 in order that heat exchange may take place most readily.

25 In heat exchangers of the old type referred to above provision had to be made for cleaning in order to avoid the accumulation of sediment in the headers. For this purpose clean-out plugs were necessary. It is a secondary object of the present invention to provide a construction in which the deposition of sediment is prevented and also complete draining may take place with the avoidance of possibility of freezing in cold weather when, for example, the heat exchanger takes the form of a cooler for milk.

35 Other detailed objects of the invention will become apparent from the following description read in conjunction with the accompanying drawings in which:

40 Fig. 1 is a front elevation partly in section of an embodiment of the invention consisting specifically of a cooler for milk or the like provided

with a series of tubes over which the milk flows, which tubes carry a stream of cooling fluid;

Fig. 2 is an end elevation of the same also partially in section; and

Fig. 3 is a fragmentary enlarged sectional view showing details of construction.

Figs. 4 and 5 are sectional views of modifications of the construction of Fig. 1.

The cooler comprises two vertically arranged headers 2 and 4 each consisting of brass, copper or other suitable tubing provided with lateral openings for the reception of tubes 6. These tubes 6 project into the headers through the openings and are secured therein, for example, by brazing, the joints being preferably flooded with solder to insure tightness. As illustrated specifically in the modification shown, each of the tubes 6 has one end cut off at right angles to its axis as indicated at 8 and its other end beveled as indicated at 10, the beveled end being truncated as indicated at 12. By choosing the tubing so that the headers have a slightly greater inside diameter than the external diameter of tubes 6, it will be obvious that the beveling at 10 will cause the beveled ends of the tubes to lie in close proximity to the inner walls of the headers. Briefly, the arrangement is such that a tight fit is avoided although it will be clear that with suitable beveling a substantially tight fit may be produced. The truncation at 12, in fact, is to prevent a tight fit and permit slight leakage past the beveled ends for the purpose of draining the portions of headers thereabove, such as at 14, above the end of one tube and below the end of a higher tube. The tubes are preferably of the cross-section illustrated in Fig. 2, having grooves 7 provided at their lower sides.

45 Instead of the arrangement which is illustrated in Fig. 1, it will be obvious that the beveling may take place in other fashions. For example, each tube may be beveled at both ends or alternatively every other tube may not be beveled while the intermediate tubes may be beveled at both ends. By either of such arrangements it will be obvious that communication in a header between pairs of tubes may be prevented, while free communication is provided between the tubes of any of the pairs.

50 Thus, in Fig. 4, each tube 60 is bevelled at both ends, so as to allow, or compel, as in the arrangement of Fig. 1, a free passage through all the tubes in series; while in Fig. 5 alternate tubes 61

are bevelled at both ends, while the intermediate tubes 62 are not bevelled at either end.

An inlet 16 is provided at the bottom of one of the headers, the lower end of which is closed by means of a washer 18 and a plug 20 of solder or the like. The washer is preferably provided to prevent the formation of a pocket below the entrance of the lowermost tube 6. An outlet 22 is provided at the top of one of the headers.

10 At the top of the cooler is arranged a feed trough 24 adapted to receive milk from a tank illustrated at 26 provided with an outlet valve 27 which milk will flow downwardly over the tubes, being cooled by the contents thereof and will eventually drip into the receiving trough 28 from which it is discharged through an outlet 30. The receiving trough 28 is preferably carried by means of hooks attached thereto and engaging the inlet 16 and a projection 32 secured to the opposite header. The device may be supported by a bracket engaging beneath the outlet 22 and a stud or the like such as indicated at 34.

25 By reason of the fact that the beveled or mitered ends of the tubes do not completely close off the headers by reason of both clearance and the definite passages provided by the truncations at 12, it will be seen that there is no chance for the collection of sediment within the headers and, furthermore, complete drainage will result when 30 the liquid is drawn from the cooler so that there will be none collecting in any pockets which might freeze in cold weather and damage or block the cooler.

35 The simplicity of the construction results in cheapness, the attachment of the tubes 6 to the headers by brazing and/or soldering may be carried out readily and without danger of warping of the tubes so that both the cooling tubes 6 and the headers may be produced of thin walled tubing. As a result, lightness and efficient heat 40 exchange are provided. While the specific embodiment disclosed is a cooler it will be obvious that the construction is equally applicable to the formation of a heater in which case the fluid 45 would be heated and pass through the series of tubes while heating fluid would be guided about such tubes or the tubes exposed directly to a flame. It will be obvious that various changes may be made in the invention without departing from 50 the spirit thereof as defined in the following claims.

What I claim and desire to protect by Letters Patent is:

1. A heat exchanger including tubular headers having lateral openings therein, and tubes joining the headers and communicating through said openings with said headers, at least some of said tubes having bevelled ends extending into the headers closely adjacent their inside walls so as to provide a free passage through all the tubes in series, but spaced therefrom to provide for a restricted flow through the length of the header for the removal of sediment. 5

10 2. A heat exchanger including tubular headers having lateral openings therein, tubes joining the headers and extending through said openings into the headers, and means for restricting communication within the headers between pairs of tubes while providing free communication between members of each pair, said means including bevelled ends of certain tubes within the headers lying closely adjacent the inside walls of the headers, said bevelled ends being spaced from the inside walls of the headers to provide for a 15 restricted flow through the length of each header for the removal of sediment. 20

25 3. A heat exchanger including tubular headers having lateral openings therein, tubes joining the headers and extending through said openings, and means for restricting communication within the headers between pairs of tubes while providing free communication between members of each pair, said means including bevelled ends of certain tubes within the headers lying closely adjacent the inside walls of the headers, said bevelled ends being spaced from the inside walls of the headers to provide for a 30 restricted flow through the length of each header for the removal of sediment. 35

40 4. A heat exchanger including tubular headers having lateral openings therein, and tubes of slightly less inside diameter than the headers communicating through said openings with said headers, at least some of the tube ends extending into the heads and being bevelled so that the bevelled ends lie in close proximity to the inner walls of the heads and so as to provide a free 45 passage through all the tubes in series, the bevelled ends being truncated so as to provide for a restricted flow through the length of the header. 50
